UNITED STATES PATENT OFFICE.

CHARLES COLOSSE HALSTEAD, OF BLODGETT, MISSOURI.

STOVEPIPE.

SPECIFICATION forming part of Letters Patent No. 703,702, dated July 1, 1902.

Application filed February 17, 1902. Serial No. 94,509. (No model.)

To all whom it may concern:

Be it known that I, CHARLES COLOSSE HALSTEAD, a citizen of the United States, residing at Blodgett, in the county of Scott and State 5 of Missouri, have invented certain new and useful Improvements in Stovepipes, of which the following is a full, clear, and exact description, reference being had to the accompanying drawings, forming a part hereof.

10 My invention has relation to improvements in stovepipes; and it consists in the novel construction of pipe more fully set forth in the specification and pointed out in the claims.

In the drawings, Figure 1 is an elevation of 15 one of the pipe-sections shown in its distended position. Fig. 2 is a similar view showing the same snugly embracing a contiguous section. Fig. 3 is a transverse section on line 3 3' of Fig. 2, and Fig. 4 is a similar section on line 20 4 4' of Fig. 2.

The object of my invention is to construct a stovepipe-section which can be readily coupled to the next contiguous section, forming therewith a tight joint, such joint being effected by the drawing together of the adjacent overlapping edges of the pipe, as will 25 more fully appear from a detailed description of the invention, which is as follows:

Referring to the drawings, P represents the 30 pipe-section, and P' one of the contiguous sections. Disposed adjacent to the inner overlapping edge of the pipe is a slot 1, inclined to said edge at an acute angle, there being formed along the major portion of the same 35 edge a series of parallel slots 2 3 4, disposed in planes at right angles to the axis of the pipe. Disposed adjacent to the outer overlapping edge of the pipe and parallel to said edge is a slot 1', a sliding wing-bolt 5 being 40 passed through both slots. Carried by the overlapping edge also are a series of rivets 6, whose shanks loosely pass through the parallel slots 2 3 4, a fixed rivet 7 securing the seam formed by the overlapping edges at the opposite 45 end of the pipe. When the sliding bolt 5 is shoved to the upper ends of the slots 1 1', the peripheral dimensions are enlarged at that end of the pipe a distance equal to the base

of a triangle whose hypotenuse is the slot 1 and whose perpendicular is the slot 1'. At 50 the same time the perimeter along the edges is enlarged to progressively-diminishing distances substantially equal to the progressively-diminishing transverse slots 2 3 4, the rivet 7 serving as a pivot for said distending 55 edges. By inserting a pipe-section P' into the upper end of the pipe P and then shifting the bolt 5 to the opposite ends of the slots 1 1' the overlapping edges will be drawn together, and thus one pipe-section can be readily coupled 60 to the next succeeding one, as is obvious. (See Fig. 2.) The next lower section P' of course receives the base of the pipe immediately above it, so that a number of sections 65 can be coupled at a moment's notice, and this (in a measure) independent of any variation in the cross-sectional areas of the pipes. The rivets 6 serve to guide the edges in their movements, as is obvious, the rivets in other respects serving their ordinary function of 70 holding the overlapping edges of the pipe together.

Having described my invention, what I claim is—

A stovepipe comprising a section having 75 overlapping edges, the inner edge having at one end an inclined slot located adjacent thereto, and the outer edge having a slot parallel therewith, a sliding bolt operating in said slots, a series of rivets carried by the outer lap 80 of the pipe, the inner lap having disposed a series of transverse closed slots of progressively-diminishing dimensions for the reception of the rivets, the inner ends of said transverse slots and the adjacent end of the inclined slot being disposed in a line substantially parallel to the edge of the inner lap, and a fixed rivet securing the overlapping edges 85 at the opposite end, substantially as set forth.

In testimony whereof I affix my signature 90 in presence of two witnesses.

CHARLES COLOSSE HALSTEAD.
